(57) **CLAIM**

The ornamental design for a stackable container system with handle, as shown and described.

DESCRIPTION

FIG. 1 is a front elevation view of the stackable container system with handle (the rear elevation view is symmetrical to the front elevation view);

FIG. 2 is a left, side elevation view thereof (the right, side elevation view is symmetrical to the left, side elevation view);

FIG. 3 is a top plan view thereof;

FIG. 4 is a bottom plan view thereof; and,

FIG. 5 is a perspective view thereof.
